VENETIAN BLIND LADDER AND LIKE WEBBING

George Frederick French and Roger French, Hale, England; Roger French, Alfred Hanson, and Neville Christopher O'Brien, executors of the estate of George Frederick French, deceased, assignors to said Roger French

Application November 6, 1951, Serial No. 255,088

Claims priority, application Great Britain
November 7, 1950

10 Claims. (Cl. 139—384)

This invention relates to Venetian blind ladder and like webbing of the kind comprising two or more outer or main bandings between which are woven or partly woven cross straps arranged in one or more rows and in which the cross straps in any one row, or in laterally overlapping rows, are of such length as to overlap longitudinally i. e. in their length so that one set of warps initially cross over through another. Such overlap may provide the required overlap for the blind laths.

While such webbing is primarily known and used for Venetian blinds, it has other uses, for example as a lining for headgear to hold cork or like inserts between the cross straps, furniture, beds, upholstery, but for convenience such webbing will be referred to hereinafter by the generic term "ladder webbing."

Examples of ladder webbing of the kind above referred to are described in our prior British patent specification No. 512,835 particularly with reference to Figs. 11, 12 and 13. Whilst such webbing may easily be made with the cross straps unwoven, certain problems arise, when such cross straps are to be woven or partly woven, due to the combined longitudinal and lateral overlap. For example, in a simple arrangement in which there are two sets of warp threads for the cross straps (one set for each alternate cross strap) due to such combined overlap the warps of one set have to pass through the warps of the other alternately in the length of each cross strap. In consequence, such kind of ladder webbing has so far only been made with unwoven or weftless cross straps and the present invention has for its object to provide an improved ladder webbing and method of making the same with woven or partly woven cross straps.

The main object of the invention is to provide ladder webbing of the type described hereinbefore having an improved character which enables production costs to be reduced by simplification of the weaving process and increased loom speed.

A further object of the invention is to provide ladder webbing of the type described hereinbefore which whilst lighter and narrower than known types of ladder webbing, maintains a given tensile strength.

A still further object of the invention is to provide such ladder webbing in which the whole or only certain parts of the cross straps are woven and in which unwoven warps are defined by adjacent woven portions. By "buttonholes" are meant apertures through which lifting cords or the like may be passed.

These and many other objects and advantages will be apparent from the following description and claims.

The invention will be described further by way of example with reference to the accompanying drawings in which:

Fig. 1 is a perspective view of one example of ladder webbing made in accordance with the present invention and having two main bands and a single row of cross straps in line;

2

Fig. 2 is a fragmentary view of a modification of the cross straps shown in Fig. 1;

Fig. 3 is a fragmentary view of a further modification of one of the cross straps shown in Fig. 1;

Fig. 4 is a perspective view showing a modification of Fig. 1;

Fig. 5 is a fragmentary view of a further modification of a cross strap made in accordance with the invention;

Fig. 6 is a perspective view of a still further modified construction.

In one example of the invention as illustrated in Fig. 1 ladder webbing having a single longitudinal row of cross straps 11 between main bandings 25, 26, formed from two sets of warp threads and overlapping in their length, the webbing is woven with four shuttles as for the previous ladder web, in which the two middle shuttles weave the warps of the staggered two rows of cross straps, but with this difference that, when the crossing over of the strap warps is effected the shuttle which has previously been weaving a portion of one cross strap, is now used to weave a similar portion of the consecutive cross strap. Thus, from the point of such cross over, each strap at one end is woven with weft 12 by one shuttle and at the other end is woven with weft 13 by the other of the two shuttles allocated for weaving the cross straps.

Such weaving of the cross straps may be effected so that, in the finished article the whole of each strap is woven, there being no visible gap in the weft where the change-over of the weft occurs; or the shedding may be arranged (Fig. 2) so that there is a central unwoven part 14 through which lifting cords for a Venetian blind may be threaded, or, in a further modification (Fig. 3) a pair of thicker warp threads 15, 16 may be provided in each strap 11 which will take any wear due to the passage of the lifting cords as the blind is raised and lowered. Also, as has been previously suggested, only some of the strap warp threads may be woven the remainder 17 being weftless so that the blind laths may be held between the woven and unwoven warp threads and the lath held in position (Fig. 4).

In a further modification shown in Fig. 5, the shedding is effected to produce a button-hole 18 in each cross strap 11. This is possible because, during the binding-in of the ends of one set of warps for the cross straps 11, both strap shuttles are made available for weaving the centre button-hole portion 18 of the said cross strap 11. Thus, in any one cross strap the weft 12 from one shuttle will be continuous from one end and extend along one side of the button-hole 18, while the other side of the button-hole 18 and the other end of the strap 11 will be woven by weft 13 from the other shuttle. The button-hole 18 can therefore be made without increasing the number of shuttles, i. e. still using only 4 shuttles and can extend for the combined length of the top and bottom binding-in.

It will of course be appreciated that, in the button-hole construction, while both the intermediate shuttles are being used for weaving the two halves of the cross strap it will not be possible to use either of these shuttles for the purpose of strengthening the binding-in as is done in accordance with our earlier British Patent No. 453,832. In all other examples it is equally to be appreciated that the use of the cross strap shuttles for strengthening the binding-in can be adopted.

The improved construction makes it possible to produce a narrower and lighter ladder webbing yet having a broader and stronger lath strap by employing more strap warp threads. Such improved webbing will be quicker and easier to manufacture and also cheaper. The actual shedding can be simplified to eliminate some of the major

changes thus reducing the shock and requiring less skill and maintenance and enabling the loom speed to be increased. For a cross strap of previously determined tensile strength it is possible to have wider cross strap with fewer picks which will consequently give quicker production and cheaper cost and at the same time retain its tensile strength. The partly woven, partly weftless form has advantages over the weftless form described in our previous patents in that the partly woven strap is enough to prevent the weftless strap warp thread portion from spreading so as to be visible at the sides of the main bands. Thus, for example with the improved construction of ladder web narrower outer bandings can be used whilst the present strap web width could be retained, or increased if necessary, thereby giving equal or greater purchasing power of the straps to the body webs than in the previously known constructions. Further, the laths are held centrally of the outer bandings.

With body webs 1" wide as against the present 1½" the cost of raw materials would be reduced by approximately one-third. Again, loom efficiency would be increased by the fact that approximately one-third more running time would be provided for each weft package on the bandings or body webs. The method of lifting the strap warps may be such that heavy lifts (i. e. over three or four shuttles) could be eliminated thereby allowing the loom to be run at a higher speed.

Instead of keeping the cross straps of the same width as at present which is substantially a practical maximum width, the said strap width may be increased and strengthened by the introduction of extra threads giving a resultant firmer binding-in and whilst an increase may apparently have a disadvantage it does in fact leave a substantial advantage in that the picks per inch could be reduced, enabling the rate of production to be increased whilst such cross straps would still retain their former strength of binding-in to the outer bandings. Another constructional advantage where the cross straps are in a longitudinal line is not only that the warp tensions in the fabric are balanced, but also the same amount of weft is drawn from the shuttles at each pick, whereas with the staggered cross strap method this was not possible, the weft being pulled off the shuttles unequally at each side.

In a further extension of the principle of the invention cross straps 11 (see Fig. 6) need not be wholly in line but may overlap laterally to a greater or lesser degree.

What we claim is:

1. A ladder webbing comprising at least two outer main bandings and at least one row of cross straps bound in at their ends between any adjacent two main bandings, successive cross straps being of such length that in-line portions thereof overlap longitudinally, so that one set of warp threads initially cross over through another set, successive cross straps each having portions at least thereof relative to and between its bound-in ends woven, one portion with picks of one common weft thread and another portion with picks of a different common weft thread.

2. A ladder webbing comprising at least two outer main bandings and at least one row of cross straps bound in at their ends between any adjacent two main bandings, successive cross straps being formed alternately from two sets of warp threads and being of such length that in-line portions thereof overlap longitudinally, so that one set of warp threads initially cross over through another set, successive cross straps each having portions at least thereof relative to and between its bound-in ends woven, one portion with picks of one common weft thread and another portion with picks of a different common weft thread.

3. A ladder webbing comprising at least two outer main bandings and at least one row of cross straps bound in at their ends between any adjacent two main bandings, successive cross straps being of such length that in-line portions thereof overlap longitudinally, so that one set of

warp threads initially cross over through another set, each successive cross strap being at least partially woven with picks of at least two different common weft threads.

4. A ladder webbing comprising at least two outer main bandings and at least one row of cross straps bound in at their ends between any adjacent two main bandings, successive cross straps being of such length that in-line portions thereof overlap longitudinally, so that one set of warp threads initially cross over through another set, successive cross straps each having like portions at least thereof relative to and between its bound-in ends woven, one portion with picks of one common weft thread and another portion with picks of a different common weft thread.

15 5. A ladder webbing comprising at least two outer main bandings and at least one row of cross straps bound in at their ends between any adjacent two main bandings, successive cross straps being of such length that in-line portions thereof overlap longitudinally, so that one set of warp threads initially cross over through another set, successive cross straps each having at least two different portions woven between its bound-in ends, one portion of each cross strap being like one portion of each other cross strap and all such like portions being woven with picks of one common weft thread, another portion of each cross strap being like another portion of each other cross strap and all such other like portions being woven with picks of a different common weft thread.

20 6. A ladder webbing comprising at least two outer main bandings and at least one row of cross straps bound in at their ends between any adjacent two main bandings, successive cross straps being of such length that in-line portions thereof overlap longitudinally, so that one set of warp threads initially cross over through another set, the same part, relative to and between its bound-in ends, of each successive cross strap being woven with picks of one common weft thread and another corresponding part between the bound-in ends of each successive cross strap being woven with picks of a different common weft thread,

25 40 said two parts defining on each cross strap a portion of unwoven warp threads through which lifting cords may be passed.

7. A ladder webbing comprising at least two outer main bandings and at least one row of cross straps bound in at their ends between any adjacent two main bandings, successive cross straps being of such length that in-line portions thereof overlap longitudinally, so that one set of warp threads initially cross over through another set, corresponding halves, relative to their bound-in ends, of each cross strap being woven with picks of one common weft thread and the other halves with picks of a second and different common weft thread.

45 55 8. A ladder webbing comprising at least two outer main bandings and at least one row of cross straps bound in at their ends between any adjacent two main bandings, successive cross straps being of such length that in-line portions thereof overlap longitudinally, so that one set of warp threads initially cross over through another set, the same part, relative to and between its bound in ends and being less than half thereof, of each successive cross strap being woven with picks of one common weft thread, and another corresponding part of each successive cross strap between its bound-in ends and being also less than half thereof, being woven with picks of a second and 60 65 different common weft thread, said two parts defining on each cross strap a portion of unwoven warp threads through which lifting cords may be passed.

9. A ladder webbing as set forth in claim 8 in which two of said warp threads are of extra thickness, between which said lifting cords may be passed.

10. A ladder webbing comprising at least two outer main bandings and at least one row of cross straps bound in at their ends between any adjacent two main bandings, successive cross straps in each row being staggered transversely but having in-line portions thereof overlapping

longitudinally, so that one set of warp threads cross over and at least partially through another set, successive cross straps each having portions at least thereof relative to and between its bound-in ends woven, one portion with picks of one common weft thread and another portion with picks of a different common weft thread.
